UNITED STATES PATENT OFFICE.

LEOPOLD HEINS, OF NEW YORK, N. Y.

IMPROVEMENT IN PILE REMEDIES, &c.

Specification forming part of Letters Patent No. 122,608, dated January 9, 1872.

SPECIFICATION.

To all whom it may concern:

Be it known that I, LEOPOLD HEINS, of the city, county, and State of New York, have invented a certain new and Improved Medicament for Treating and Curing Piles and similar diseases of the bowels and fundament or rectum; and I do hereby declare that the following is a full description of the same.

The nature of my invention consists in treating the patient with a liquid medicine to act on the stomach and bowels to remove all exciting causes to the piles, and the application of an ointment to the rectum, per anus, to heal and cure them.

These medicines are composed of the following ingredients, to wit: First preparation, sample one, senna-leaves; first preparation, sample two, aliva; first preparation, sample three, pure water; first preparation, sample four, alcohol; first preparation, sample five, compounded medicine. Second preparation, sample six, beeswax; second preparation, sample seven, Venice turpentine; second preparation, sample eight, castor-oil; second preparation, sample nine, compounded ointment.

The first preparation is made thus: In about one quart of water is put about one ounce of senna-leaves and about one-fourth of an ounce of aliva, and the whole boiled freely for about three minutes. The tea or liquor is then taken from off the fire and allowed to get cold, when the clear liquor is strained off into a suitable vessel, and about one pint of ninety-five per cent. alcohol added to it and well and thoroughly incorporated therewith to complete the first preparation or compound.

The second preparation is made as follows: A half a pound of pure beeswax is first melted in a suitable vessel, to which, when melted, half a pound of Venice turpentine and a half a pound of castor-oil are added, and the whole

thoroughly mixed together to make a homogeneous ointment to complete the second preparation or compound.

These two preparations or compounds are administered to the patient for curing the piles as follows: The patient is first given about one-half gill of the first compound diluted in about the same quantity of water for the purpose of acting on the stomach and bowels to excite them into action to throw off all impurities therein, and give a healthy tone to the mucous membrane lining them. Should this first dose not produce an evacuation of the bowels within twelve hours the dose is to be repeated, when an operation will be produced without fail. As soon as the effects of the medicine have ceased the patient, on going to bed at night, inserts a small ball of soft cotton well saturated with the second preparation or ointment into the rectum, per anus, to remain there till morning, when a natural stool will be produced, and the wad of cotton discharged from the body. This treatment with the ointment will be repeated every night for three or four weeks for very obstinate cases, interspersed every six days by a dose of the first preparation.

In ordinary cases of piles, after taking the first dose of the first preparation, and the use of the ointment one or two days, a cure is effected; but in all cases a radical cure has been effected within three to four weeks.

Having now described my invention, I will proceed to set forth what I claim and desire to secure by Letters Patent of the United States.

I claim—

The pile remedy, hereinbefore described, consisting essentially of the combination of the ingredients, as herein specified.

LEOPOLD HEINS.
